UNITED STATES PATENT OFFICE

2,098,770

SEWING MACHINE

Sydney Zonis, Bridgeport, Conn., assignor to The Singer Manufacturing Company, Elizabeth, N. J., a corporation of New Jersey

Application October 22, 1935, Serial No. 46,071

30 Claims. (Cl. 112—81)

This invention relates to improvements in sewing machines and has for its primary object to provide a stitch-forming mechanism of simple construction and adapted for high speed operation.

The invention has for a further object to provide a simple form of thread-handling mechanism for cooperation with an endwise reciprocating and laterally vibratory thread-carrying needle in the formation of stitches.

More specifically, the present invention has for an object to provide a two-needle hemstitching machine with thread-handling mechanism of simple construction and adapted to form chain-stitch open-work seams.

With the above and other objects in view, as will hereinafter appear, the present invention consists in the devices, combinations and arrangements of parts hereinafter described in connection with the accompanying drawings which illustrate a preferred embodiment of the invention and in which:

Fig. 1 is a front side elevation, with the bed-plate partly in section, of a single-thread chain-stitch hemstitching machine containing the improved thread-handling mechanism. Fig. 2 is a bottom plan view of the hemstitching machine. Fig. 3 represents an enlarged cross-section of the machine bed-plate, substantially on the line 3—3 of Fig. 1. Fig. 4 represents a detail view of the feed-lift actuating mechanism. Fig. 5 represents a vertical longitudinal section of the machine bed-plate, through the throat-plate needle-apertures and with the loopers in loop-seizing position. Fig. 6 is a top-plan view showing the looper and needle-guard actuating mechanism, in the position thereof corresponding to that illustrated in Fig. 5. Fig. 7 represents an enlarged detail view, partly in section, of an auxiliary tension device for controlling the slack needle-thread. Fig. 8 is a detail view illustrating the position of the thread-loop detained by the looper behind the needle during the second penetration of the piercer-aperture by the needle. Fig. 9 represents the needle-thread pull-off device, in a cross-sectional view of the machine bracket-arm substantially on the line 9—9 of Fig. 1. Fig. 10 represents a vertical section of the machine bracket-arm substantially on the line 10—10 of Fig. 1 and illustrating the intermittent-tension in released position. Fig. 11 represents a horizontal section of the intermittent tension in closed position. Fig. 12 is a top plan view of the throat-plate. Fig. 13 represents a longitudinal section

of the throat-plate substantially on the line 13—13 of Fig. 12.

The needle and feed-actuating mechanisms of the present hemstitching machine correspond substantially with the disclosures in the U. S. Patents to G. M. Eames et al., No. 1,721,072, July 16, 1929, and to A. H. DeVoe, No. 1,940,399, Dec. 19, 1933. It is to be understood, however, that the present invention is not limited to the details of construction of the needle and feed-actuating mechanisms disclosed in said prior patents and herein described in more general terms.

As illustrated in the drawings, the present hemstitching machine has the usual frame comprising a bed- or cloth-plate 1, from which rises a hollow standard 2 of an overhanging bracket-arm 3 terminating in a head 4.

Journalized in suitable bearings provided in the overhanging bracket-arm is a rotary main shaft 5 carrying at one end a belt-pulley 6 and at its opposite end a crank-disk 7. The crank-disk 7 is connected by a link 8 with the needle-bar 9 journaled for vertical reciprocation in suitable bearings provided in the head 4. The needle-bar 9 carries at its lower end a supporting plate 10 pivotally sustaining a pair of needle-carriers 11 and 12 for adjustment toward and from each other. Carried by the respective needle-carriers are needles 13 and 14, and also upstanding guide-rods 15 and 16 vertically reciprocated with the needle-bar.

The guide-rod 15 passes through a transversely apertured swivel-pin 17 journaled in a bearing boss at the free end of a crank-arm 18 carried by a horizontally disposed rock-shaft 19 journaled in the bracket-arm head 4. The guide-rod 16 is similarly controlled by a swivel-pin 20 journaled in a crank-arm 21 of a rock-shaft 22 substantially parallel to the rock-shaft 19 and also journaled in the head 4. As more fully disclosed in the prior U. S. Patent No. 1,940,399, the respective rock-shafts 19 and 22 are operatively connected to pitman rods 23 and 24 deriving endwise movements from a rotary cam 25 secured for rotation with a spur-gear 25' driven from the main shaft 5 to rotate once for three rotations of said main-shaft.

The machine has the usual piercer mechanism comprising a main piercer-and-shaper 26 carried by a piercer-bar 27 journaled for vertical reciprocation in the bracket-arm head 4, said piercer being actuated by the usual connections with a horizontally disposed rock-shaft 28 journaled in suitable bearings provided at the rear side of the bracket-arm 3. Clamped upon the

rock-shaft 28 is a crank-arm 29 (Fig. 9) pivotally connected to one end of a pitman 30 of which the opposite end is provided with a strap embracing an eccentric 31 upon the main-shaft 5. 5 The usual auxiliary piercer 32 is preferably mounted upon the needle-bar plate 10 so as to be disposed in front of the main-piercer 26, the latter being recessed at opposite sides thereof to receive the needles in their narrowly spaced reciprocations. The main-piercer 26 reciprocates once for each needle reciprocation, but the relative timing is preferably such that said main-piercer both descends and rises in advance of the corresponding movements of the needles. Being carried by the needle-bar, the auxiliary piercer 32 of course reciprocates with the needles, but in a single path.

Secured upon the cloth-plate 1 is a throat-plate 33 provided with parallel feed-dog slots 34 20 extending along opposite sides of a work-supporting bar 35. The throat-plate bar 35 has an auxiliary-piercer aperture 36, rearwardly of which are the adjacent needle-apertures 37, separated by a guard-plate 38 extended to depend vertically 25 from the underside of the throat-plate and in the direction of feed of the work. The guard-plate 38 has a vertical slot 39 adjacent to and connecting the front ends of the needle-apertures 37, said slot 39 providing clearance for the main-piercer 26. The slot 39 terminates at its lower end in a needle-guiding web 40 of which the opposite faces are divergently inclined downwardly to guide the needles in their narrowly spaced reciprocating movements. The guard-plate 38 serves to prevent entanglement of the adjacent limbs of the needle-thread loops.

The upper face of the throat-plate bar 35 is provided with a short groove 41 extending from the auxiliary-piercer aperture 36 to the piercer-slot 39. The work-penetrating movement of the auxiliary-piercer 32 forms a burr at the under side of the work, and the groove 41 provides a clearance for said burr, so that the aperture as formed by the auxiliary piercer retains its shape 45 until entered by the main-piercer 26. The spacing of the piercers corresponds, of course, with the amplitude of feed and, as the main-piercer cleanly enters the aperture as initially formed by the auxiliary-piercer the liability of breaking the 50 material threads by the main-piercer is eliminated and the appearance of the product is enhanced by the resulting uniform spacing of the hemstitch-seam apertures.

The upper edge 42 of the guard-plate 38, rearwardly of the piercer-slot 39, is likewise cut away to obviate interference with the cross-bars of the hemstitch seam, while feeding the work. Preferably the edge 42 is inclined upwardly from the piercer-slot 39 to merge with the upper face 60 of the throat-plate bar 35 at substantially the rearward ends of the needle-apertures 37, said needle-apertures being preferably slightly elongated in the direction of seam formation to facilitate the formation of chain-stitches. Rearwardly of the needle-apertures 37, the throat-plate bar 35 is provided with parallel grooves 43 affording seam clearances.

Operating through the throat-plate slots 34 is a lower four-motion feed-dog 44 opposed by a 70 presser-foot 45 of any usual or suitable construction. The feed-dog 44 is carried by a feed-bar 46 pivoted, at one end, to a rocker 47 carried by a feed-advance rock-shaft 48. At its opposite end, the feed-bar is operatively engaged by a 75 rock-arm 49 of a feed-lift rock-shaft 50, said

rock-shafts 48 and 50 being journaled in suitable bearings provided at the under side of the bed-plate 1. The feed-advance rock-shaft 48 carries a crank-arm 51 pivotally connected to the lower end of a link 52, of which the upper end is adjustably secured upon a segment-lever 53 disposed outside of the bracket-arm. The segment-lever 53 is secured upon a fulcrum-shaft 54 journaled in the bracket-arm standard 2, said segment-lever carrying a roller-stud 55 entering a 10 cam-groove 56 formed in the side face of a feed-cam 57. The feed-cam 57 is secured for rotation with the spur-gear 25' in the usual manner and is so formed as to impart a work-advancing impulse to the feed-dog 44 while the needles are 15 out of the work, and a retarded return movement during the formation of three successive stitches.

Clamped upon the feed-lift rock-shaft 50 is a crank-arm 58 connected by a link 59 to a rock-arm 60 pivotally mounted upon the fulcrum-shaft 54. The rock-arm 60 carries a roller-stud 61 entering a feed-lift cam-groove 62 in the side face of the spur-gear 25'. The cam-groove 62 is so formed that the feed-dog 44 is raised into 25 engagement with the work during the work-advancing movement thereof and remains lowered, out of engagement with the work, during the retarded return movement of the feed-dog.

Journalized in bearing-lugs 63, 64 and 65, depending from the cloth-plate 1, is a rotary looper-actuating shaft 66 connected to be driven from the main-shaft 5 in one-to-one relation therewith. Secured upon said shaft 66, adjacent to the bearing-lug 63 is a spur-gear 67 in driving engagement with a similar gear 68 upon a looper-shaft 69 journalized in the bearing lug 63 above and substantially parallel to the looper-actuating shaft 66. Carried by the looper-shaft 69 is a rotary looper formed with a loop-seizing beak 70 40 and with a loop-detaining and -spreading wing 71. Between the heel 72 of the beak-forming portion of the looper and the wing 71 is a throat 73 which receives the thread-loop *a*, *a'*, seized by the looper from the needle and in which throat 45 the thread-loop is detained in spread condition until after the looper has seized a succeeding thread-loop and has carried it through the previously formed and detained thread-loop. In the preferred embodiment of the invention, the loop- 50 beak path of rotation is disposed between the spaced work-penetrating paths of the needle 13, the looper-beak 70 cooperating with the needle 13 at the side thereof remote from the needle 14 and having its loop-seizing movement in the direction of feed of the work.

Cooperating with the needle 14, at the side thereof remote from the needle 13, is a rotary looper 74 similar to the above described looper, but reversely constructed so that the beak of said 60 looper 74 likewise has its loop-seizing movement in the direction of feed of the work. The looper 74 is carried by a looper-shaft 75 journalized in the bearing-lug 64 in alinement with the looper-shaft 69, said shaft 75 being connected to the actuating 65 shaft 66 by spur-gears 76 and 77.

Referring more particularly to Figs. 6 and 8 of the drawings, it will be noted that the alined axes of rotation of the loopers are disposed in a vertical plane which is rearward of the vertical 70 plane containing the paths of reciprocation of the needles 13 and 14, whereby the bottoms of the looper-throats 73 are likewise positioned rearwardly of the needles. This arrangement has the advantage that the needles 13 and 14 thereby 75

descend, with certainty, in front of both limbs *a*, *a'*, or *b*, *b'* of the previously formed needle-thread loops held detained on the loopers, regardless of the fact that the work is advanced only 5 once during the formation of three successive stitches and that the needles **13** and **14** are vibrated laterally to descend in different paths.

Cooperating with the respective needles **13** and **14**, at the looper sides thereof, are needle-and-loop guards **78** and **79**. The guard **78** has a supporting shank **80** mounted in a guideway **81**, formed in the bearing-lug **63**, for horizontal sliding movements of the guard transversely of the line of seam formation. The guard-shank **80** 10 is held in its guideway by a cover-plate **82**, removably secured upon the bearing-lug **63** by screws **83**. Depending from one end of the guard-shank **80** is a roller **84** entering a cam-groove **85** formed in a barrel-cam **86** secured upon the 15 outer end of the looper-shaft **69**. The end of the guard **78** adjacent to the needle **13** is provided with a needle-receiving notch **87** and, rearwardly of said notch **87**, with a loop-detaining notch **88**. The notch **87** is preferably so formed 20 that, when the needle **13** is engaged by the walls of said notch **87**, a thread-clearance is provided between the needle and the bottom of the notch **87** for the limb of the thread-loop formed by the needle and extending to the work. While, 25 therefore, the needle-engaging notch **87** does not interfere with formation of the needle-thread loops and the presentation of said loops to the looper, the rear wall of said notch **87** acts as an abutment for the loop-limb *a*, to oppose yielding 30 movement of said loop-limb responsive to initial entry of the looper-beak **70** into the thread-loop. The loop-detaining notch **88** is adapted to receive both limbs *a*, *a'* of the thread-loop detained in the throat **73** of the looper, said guard-notch **88** functioning primarily to insure against 35 premature casting off by the loopers of the loop *a*, *a'*, thereby to minimize liability of thread entanglement from undue twisting of prematurely cast-off loops.

Bearing in mind that the needle **13** penetrates the work at points spaced crosswise of the line of feed and that the path of looper rotation is fixed, it will be understood that the corresponding looper-detained loops will extend in different directions from the work to the looper. To compensate for the different angles of the looper-detained loops, the present axis of rotation of the looper is positioned lower, relatively to the throat-plate, than as conventionally located in prior chain-stitch machines employing loopers of the present type. This arrangement favors re-entrance of the looper-detained loop by the looper after seizure of a subsequently presented needle-thread loop. Furthermore, the extension-angle 50 of the looper-detained loop is improved by the engagement of the limbs of said loop by the guard-notch **88**, which tends to determine a loop-position which is more nearly constant for the different paths of needle-reciprocation. Incidentally, the guard-notch **88** also aids in holding both limbs *a*, *a'* of the looper-detained loop rearwardly of the needle-path.

The guard **79**, which cooperates with the needle **14**, likewise has a needle-receiving notch **87'** and a loop-detaining notch **88'**, said guard having its shank **89** slidably mounted in a guideway **90** in the frame-lug **64** and retained in said guideway by a removable cover-plate **91**. The guard **79** has a depending roller **92** entering a cam-groove **93** of a barrel cam **94** carried by the

looper-shaft **75**, whereby said guard **79** is intermittently reciprocated horizontally transversely of the line of seam formation. Access to the cover-plates **82** and **91** is afforded by the usual slide-plates **95** and **96** upon the cloth-plate **1**. 5

After a work-advancing movement of the feed-dog **44**, the main-piercer **26** is closely followed in its descending movement by the needles **13**, **14**, which, at this time, descend in their narrowly spaced relation, i. e., in close proximity to the main-piercer **26**, to enter the work-aperture initially formed by the front piercer **32** and enlarged or shaped by said main-piercer. When the needles approach completion of their down-stroke, they move slightly away from each other laterally into the spaced relation which said needles occupy in their subsequent loop-presenting position. This lateral movement of the needles is derived from the rotary cam **25**, but is assisted, if necessary, by the divergent faces 15 of the needle-guiding web **40** below the throat-plate.

The needle-guards **78** and **79**, which are both dwelling in retracted positions during the beginning of said work-penetrating movement of the needles, are advanced toward the needles as the latter are approaching the lowest point of their downstroke, said needle-guards completing their advancing movement at substantially the bottom of the needle-movement to engage the needles 30 and thereby to prevent fouling of the needles and loopers. The needles now rise into loop-presenting position, the rising movement of the needles being preceded by the rising movement of the piercer **26**. 35

The beaks of the loopers enter the thread-loops presented by the needles in their initial rising movement. In the continued rotation of the loopers, said thread-loops are caught by the heels of the loopers and are detained in the 40 looper-throats until they are again entered by the beaks of said loopers.

Immediately after the seizure of the thread-loops by the loopers, the needle-guards **78** and **79** are retracted by the cams **86** and **94**, and the needles complete their rising movement. When the needles begin their succeeding descent they are moved farther apart into their more widely spaced relation, in which they now penetrate the work adjacent to and at opposite sides 50 of the work-aperture previously entered. The main piercer **26** again descends in advance of the needles, said needles being caused to slightly approach each other as they complete their downward movement to assume their proper spaced relation for subsequently presenting loops to the loopers. The time of operation of the needle-guards **78** and **79** is, of course, the same as above described in connection with the descending movement of the needles in their more 55 narrowly spaced relation. Consequently, should the needles lag in their approaching movement, as for instance by reason of close texture of the work, the notched portions **87** and **87'** of the needle-guards will engage and push the lagging needles into their proper positions with respect to the loopers. The limbs *a*, *a'* and *b*, *b'* of the loops previously formed and held spread by the loopers are engaged by the notches **88** and **88'** of the advanced needle-guards **78** and **79**, for the 60 purposes hereinbefore described. 65

The needles **13**, **14** complete their upstroke in their loop-presenting spaced relation and, in the beginning of their succeeding descent, said needles approach each other into their more nar-

rowly spaced relation to again enter the work-aperture, immediately after the third entrance of said aperture by the main-piercer 26. The needle-guards function as before described, 5 while the needles again separate slightly preparatory to rising into loop-presenting positions thereof. The feed-dog 44 remains ineffective during the above described three work-penetrating movements of the needles, but during the 10 completion of the third rising movement and the beginning of the subsequent descending movement of the needles in their narrowly spaced relation, the feed-dog 44 is raised and functions to advance the work, preparatory to a repetition 15 of the above described three-stitch cycle. The seams formed by the respective needles correspond substantially with the single-thread chain-stitch seam disclosed in the U. S. patent to A. H. DeVoe, No. 1,920,784, Aug. 1, 1933.

20 Referring now more particularly to the thread-controlling devices upon the machine bracket-arm, the needle-threads are intermittently drawn from a suitable thread-supply (not shown) by a thread pull-off mechanism comprising a 25 thread pull-off rod 97 vibrated in a path between the spaced members of an inverted U-shaped guide-post 98, secured upon the bracket-arm 3 at the rear side thereof and provided with suitable thread-guiding apertures at opposite sides 30 of the vibratory pull-off rod 97. The rod 97 is carried by an arm extending from a collar 99 clamped upon the piercer-actuating rock-shaft 28.

Operating in suitably timed relation with respect to the stitch-forming mechanism is an intermittent tension device comprising a bushing 100 threaded into the front side of the bracket-arm 3 and provided at its outer end with a peripheral flange 101, said bushing being adjustably secured by a lock-nut 102. Seated within the bushing 100 is a supporting sleeve 103 provided, intermediate its ends, with a peripheral flange 104 in engagement with the front face of the bushing-flange 101. The sleeve 103 is secured to the bushing 100, for turning adjustment therein, by a set-screw 105, said sleeve having a forwardly extending post 106 threaded upon its outer end to receive an adjusting nut 107. Extending longitudinally of the post 106, from the outer end thereof, is a slot 108 terminating at its inner end in a post-aperture 108' communicating with the interior of the sleeve 103.

Embracing the post 106 are tension-disks 109 and 110, between which is disposed a thread-separating disk 111. Mounted upon the post 106, adjacent to the outer tension-disk 109, is a tension-release disk 112 anchored against rotation by having a central web 112' thereof disposed within the post-slot 108. The tension-disks 109, 110, and the intermediate disk 111 are also restrained against rotation, and by a pin 113 extending forwardly from the sleeve-flange 104 through suitable peripheral notches in said disks. Interposed between the adjusting nut 107 and the tension-release disk 112 is the usual beehive spring 114 functioning to impose a frictional drag upon the threads passed between the tension-disks 109, 110, at opposite sides of the separating-disk 111.

70 Endwise slidable within the sleeve 103 is a tension-release pin 115 provided, within the bushing 100, with an annular shoulder 116 engaged by one end of a coil-spring 117 bearing against the inner end of the sleeve 103. The inner end 75 of the pin 115 extends through the bushing 100

into position for engagement by an eccentric or cam 118 carried by the main-shaft 5. The opposite end of the pin 115 is reduced to enter the post-slot 108 for engagement with the release-disk web 112'. A light spring 119 is interposed 5 between the tension-release disk 112 and the tension-disk 109 to exert a minimum tension upon the threads when the maximum tension is released by movement of the release-disk 112 into ineffective position, under the action of the eccentric 118. The maximum-tension timing may be varied by adjustment of the bushing 100 in the bracket-arm 3, the sleeve 103 and its securing set-screw 105 providing for correcting the position of the tension-disk anchoring pin 113, after 15 adjustment of the bushing 100, so that said pin 113 will not obstruct or divert the threads.

Inasmuch as the release-pin 115 acts directly upon the release-disk 112, the maximum tension is substantially instantaneously released and applied, the minimum tension imposed by the spring 119 remaining constant, regardless of the maximum-pressure adjustment of the spring 114.

The threads are suitably directed from the guide-post 98 to the intermittent tension device 25 above described and then to the usual thread-tensions 120 before passing to the slack-thread controller 121. From said slack-thread controller, the threads are led through take-up thread-eyes 122, carried by the needle-bar, to an auxiliary slack-controlling device, before passing to the respective needles.

Referring more particularly to Fig. 7 of the drawings, the auxiliary slack-thread controller referred to comprises a supporting post 123 suitably mounted upon the front side of the bracket-arm head 4. Embracing the post 123 are two pairs of tension-disks 124 and 125, between which pairs of tension-disks is interposed a coil-spring 126 embracing the post 123. The action of the spring 126 is limited by the hubs of cup-shaped guard-members 127 and 128 partly embracing the respective pairs of tension-disks. The guard-member 127 may be fixedly secured upon the post 123, as by solder or otherwise, while the guard-member 128 is preferably removably secured by a screw 129 threaded into the end of the post 123. The post 123 is provided with a slot 130 extending from one pair of tension-disks to the other, access to said slot being provided by a threading-slit 131 in the post midway of the length of the slot 130.

One of the needle-threads is passed between the disks 124, the inner of said disks yielding laterally to a pull upon the thread to introduce the thread, through the slit 131, into the slot 130. The other thread is introduced into said slot 130 in the same manner to pass the thread between the tension-disks 125. The pairs of tension-disks 124 and 125 impose a mild tension upon the threads, sufficient to properly control said threads between the take-up 122 and the needles.

The intermittent tension device is effective to apply its maximum frictional drag upon the threads during the period of each stitch-forming cycle beginning just before seizure of the needle-thread loops by the loopers and ending immediately prior to the setting of the previously formed stitches, the final setting of the stitches being effected by the rotating loopers and occurring as the needles begin their descent.

During the rising movement of the needles, the take-up eyes carried by the needle-bar serve to pull up the loops of thread cast off by the loopers, and it is to insure this loop-pulling-up action 75

that the maximum tension of the intermittent tension-device is applied at this time. When the eyes of the rising needles are passing through the work, sufficient friction may be imposed upon 5 the threads by the work to prevent or retard, momentarily, the drawing of the threads through the needle-eyes by the take-up. The slack-thread controller accommodates this condition by yielding to the pull upon the threads.

10 The intermittent tension-device changes its frictional drag upon the threads from maximum to minimum practically instantaneously as the needles are ending their up-stroke, so that a minimum tension may be applied during the 15 final setting of the stitches, thereby to avoid thread breakage. The frictional drag of the threads upon the loopers is sufficient to effect setting of the stitches, regardless of the fact that very little drag is imposed at this time upon the 20 threads by the tension-devices. The minimum tension remains effective until the needles have completed their descent.

While the pull-off rod happens, in the present case, to be effective upon the threads during 25 the time that the maximum tension is applied by the intermittent tension-device, this particular time of operation of the pull-off is merely incidental and is not essential to the successful operation of the machine. In fact, it is the frictional drag imposed upon the threads by the 30 member of the guide-post remote from the thread-supply which insures pulling the threads from the supply side of the pull-off rod.

It is to be understood that in certain of its aspects, the present invention is not limited to two-needle sewing machines generally or to chain-stitch hemstitching machines in particular, as certain features of the invention are obviously adapted for use in single-needle sewing 40 machines whether adapted to form lock-stitches or to form chain-stitches.

Having thus set forth the nature of the invention, what I claim herein is:—

1. In a sewing machine, a thread-carrying 45 needle having laterally spaced work-penetrating movements followed by lateral movements into a substantially constant loop-presenting position, means for actuating said needle, a rotary looper complementary to said needle in the formation of 50 chain-stitches, said looper having a loop-seizing beak and a loop-detaining wing constructed and arranged to enchain loops of thread presented to said looper by said needle, and means for rotating said looper.

55 2. In a chain-stitch sewing machine, an end-wise reciprocatory thread-carrying needle having lateral movements for penetrating the work in spaced paths and lateral movements into a substantially constant loop-presenting position, means for actuating said needle, a rotary looper 60 provided with a loop-seizing beak having a path of rotation in a plane between the work-penetration paths of said needle, said looper being constructed and arranged to enchain loops of thread presented to said looper by said needle, and means for rotating said looper.

3. In a sewing machine, a thread-carrying 65 needle, actuating mechanism for imparting end-wise reciprocatory and laterally vibratory movements to said needle, a rotary looper complementary to said needle in the formation of chain-stitches and provided with a beak having a fixed path of rotation in a plane transverse to the plane of needle vibration, said looper having its axis of rotation offset laterally from said plane

of needle-vibration, and means for rotating said looper.

4. In a sewing machine, work-feeding mechanism, a thread-carrying needle, means for vertically reciprocating said needle a plurality of 5 times for one effective work-advancing movement of said feeding mechanism, means for vibrating said needle laterally in a plane extending crosswise of the line of feed, a rotary looper complementary to said needle in the formation 10 of chain-stitches, said looper having a path of rotation about a horizontal axis extending transversely of said line of feed and disposed rearward of the plane of needle-vibration, and means for rotating said looper. 15

5. In a sewing machine, work-feeding mechanism, a thread-carrying needle, means for vertically reciprocating said needle, means for vibrating said needle laterally in a plane extending crosswise of the line of feed, a rotary looper 20 having a needle-thread-loop seizing beak and a loop-detaining throat, said looper-beak having a fixed loop-seizing path of movement in the direction of seam formation, and said loop-detaining throat being disposed rearward of the 25 plane of needle-vibration in the loop-seizing position of said looper-beak, and means for rotating said looper.

6. In a sewing machine, a reciprocatory thread-carrying needle, means for reciprocating said 30 needle, a rotary looper having a needle-thread-loop seizing path of movement at one side of said needle, means for rotating said looper, a needle-guard movable toward and from the needle-path of reciprocation at the looper side of 35 said needle, and means for actuating said needle-guard relatively to said looper.

7. In a sewing machine, a throat-plate, a reciprocatory thread-carrying needle, means for reciprocating said needle, a looper having a 40 needle-thread-loop seizing path of movement at one side of said needle, means for actuating said looper, a needle-guard having a constant needle-guiding position at the looper-path side of said needle and between said looper-path and said 45 throat-plate, and means for actuating said needle-guard to and from said constant needle-guiding position during each complete needle reciprocation.

8. In a sewing machine, a reciprocatory thread-carrying needle, means for reciprocating said 50 needle, a rotary looper complementary to said needle in the formation of stitches, means for rotating said looper, a needle-guard movable to and from a constant needle-guiding position in 55 a direction substantially parallel to the axis of rotation of said looper, and means for actuating said needle-guard to and from said constant needle-guiding position during each complete needle reciprocation.

9. In a sewing machine, a vertically reciprocatory thread-carrying needle, a horizontal-axis rotary looper complementary to said needle in the formation of stitches, a horizontally reciprocatory needle-guard movable to and from a constant 65 needle-guiding position, and means for reciprocating said needle-guard to and from said constant needle-guiding position during each complete needle reciprocation.

10. In a sewing machine, a work-feeding mechanism, a vertically reciprocatory thread-carrying needle, a rotary looper complementary to said needle in the formation of stitches and rotatable about a horizontal axis extending transversely of the line of feed, a needle-guard reciprocable to- 75

ward and from said needle in a horizontal path substantially parallel to the looper-axis of rotation, and means for reciprocating said needle-guard.

- 5 11. In a sewing machine, a thread-carrying needle, actuating mechanism for imparting endwise reciprocatory and laterally vibratory movements to said needle, a looper complementary to said needle in the formation of stitches and having a needle-thread-loop seizing path of movement at one side of said needle, a needle-guard movable to and from an effective needle-guiding position at the looper-path side of said needle, and means for actuating said needle-guard relatively to said looper.

10 12. In a sewing machine, a work-support, a vertically reciprocatory and laterally vibratory needle having lateral movements below said work-support into a loop-presenting position which is substantially constant in successive reciprocations of said needle, means for actuating said needle, a horizontal-axis rotary looper complementary to said needle in the formation of stitches, means for rotating said looper, a needle-guard movable into an effective needle-guiding position in advance of the seizure of needle-thread loops by said looper, and means for actuating said needle-guard.

- 15 13. In a sewing machine, work-feeding mechanism, a reciprocatory thread-carrying needle, actuating mechanism for imparting lateral vibratory movements to said needle in a direction substantially transverse to the line of seam formation, a horizontal-axis rotary looper complementary to said needle in the formation of stitches and having a fixed needle-thread-loop seizing path of movement at one side of said needle, means for rotating said looper, a needle-guard movable to and from a constant needle-guiding position at the looper-path side of said needle, and means for actuating said needle-guard to and from said constant needle-guiding position during each complete needle reciprocation, thereby to insure in successive stitches a substantially constant relative position of the needle and looper at the time of seizure of the needle-thread loops.

20 14. In a sewing machine, work-feeding mechanism, a vertically reciprocatory thread-carrying needle, means for vibrating said needle crosswise of the line of feed, a looper complementary to said needle in the formation of stitches and having a fixed loop-seizing path of movement at one side of said needle, a needle-guard having an effective needle-guiding position at the looper-path side of said needle, and means for reciprocating said needle-guard transversely of said line of feed to and from effective needle-guiding position.

- 25 15. In a sewing machine, a work-support, a reciprocatory thread-carrying needle, a looper having a needle-thread-loop seizing path of movement at one side of said needle, means for laterally vibrating said needle below said work-support across the path of loop-seizing movement of said looper, a needle-guard movable relatively to said needle and looper to back up the needle during its lateral movement across said looper-path, and means for actuating said needle-guard.

30 16. In a chain-stitch sewing machine, work-feeding mechanism, an endwise reciprocatory thread-carrying needle having lateral movements for penetrating the work in spaced paths and lateral movements into a substantially con-

stant loop-presenting position, means for actuating said needle, a rotary looper complementary to said needle in the formation of chain-stitches and rotatable about a horizontal axis extending transversely of the line of feed, said looper having a loop-seizing beak and a loop-detaining wing constructed and arranged to enchain loops of thread presented to said looper by said needle, means for rotating said looper, and a needle-thread-loop guard adapted to engage and control thread-loops held detained by said looper.

- 35 17. In a chain-stitch sewing machine, an endwise reciprocatory thread-carrying needle having lateral movements for penetrating the work in spaced paths and lateral movements into a substantially constant loop-presenting position, means for actuating said needle, a rotary looper having its path of rotation transverse to the path of lateral movement of said needle, said looper having a loop-seizing beak and a loop-detaining wing constructed and arranged to enchain loops of thread presented to said looper by said needle, means for rotating said looper, a needle-thread-loop guard movable relatively to said looper for engaging and controlling thread-loops held detained by said looper, and means for actuating said loop-guard.

40 18. In a chain-stitch sewing machine, an endwise reciprocatory thread-carrying needle having laterally spaced work-penetrating movements and lateral movements into a substantially constant loop-presenting position, means for actuating said needle, a rotary looper having its path of rotation in a plane transverse to the path of lateral movement of said needle, said looper being constructed and arranged to enchain loops of thread presented to said looper by said needle, means for rotating said looper, a needle-and-loop guard provided with a thread-loop receiving notch for engaging and controlling thread-loops held detained by said looper, and means for moving said guard to and from effective needle-guiding and loop-controlling position.

- 45 19. In a sewing machine, a pair of endwise reciprocatory and laterally vibratory thread-carrying needles, needle-actuating mechanism including means for vibrating said needles laterally in directions toward and from each other, and mechanism complementary to said needles in the formation of chain-stitches including a pair of rotary loopers cooperating with the respective needles at the relatively remote sides thereof in the seizure of needle-thread loops.

50 20. In a sewing machine, a pair of endwise reciprocatory and laterally vibratory thread-carrying needles, needle-actuating mechanism including means for vibrating said needles laterally in directions toward and from each other, rotary loopers cooperating with the respective needles at the relatively remote sides thereof in the formation of chain-stitches, said loopers having fixed paths of rotation in parallel planes transverse to the lateral movements of said needles, and means for rotating said loopers.

- 55 21. In a sewing machine, work-feeding mechanism, a pair of vertically reciprocatory and laterally vibratory thread-carrying needles, needle-actuating mechanism including means for vibrating said needles laterally in directions toward and from each other, a pair of horizontal-axis rotary loopers having loop-seizing beaks cooperating with the respective needles at the relatively remote sides thereof in the formation of chain-stitches, means for rotating said loopers, a work-

- penetrating piercer disposed between said needles, and means for reciprocating said piercer.
22. In a sewing machine, work-feeding means, a pair of endwise reciprocatory and laterally vibratory thread-carrying needles arranged abreast with respect to the line of feed, means for relatively vibrating said needles laterally in a plane transverse to the line of feed, horizontal-axis rotary loopers cooperating with the respective needles at the relatively remote sides thereof in the formation of chain-stitches, alined looper-carrying shafts having their axes of rotation disposed rearwardly of the plane of needle-vibration, and means for rotating said shafts.
23. In a sewing machine, work-feeding means, a pair of vertically reciprocatory and laterally vibratory thread-carrying needles arranged abreast with respect to the line of feed, needle-actuating mechanism including means for laterally vibrating said needles transversely of the line of feed, a pair of rotary loopers cooperating with the respective needles at the relatively remote sides thereof in the formation of chain-stitches, said loopers having fixed paths of rotation about horizontal axes transverse to said line of feed, and means for rotating said loopers.
24. In a sewing machine, work-feeding means, a pair of vertically reciprocatory and laterally vibratory thread-carrying needles arranged abreast with respect to the line of feed, means for laterally vibrating said needles transversely of the line of feed, rotary loopers cooperating with the respective needles at the relatively remote sides thereof in the formation of chain-stitches, horizontally disposed and alined rotary shafts carrying said loopers, a looper actuating shaft having driving connections with the looper carrying shafts, and means for rotating said looper actuating shaft.
25. In a sewing machine, work-feeding means, a pair of vertically reciprocatory and laterally vibratory needles arranged abreast with respect to the line of feed, means for laterally vibrating said needles transversely of the line of feed, rotary loopers having fixed paths of rotation and cooperating with the respective needles at the relatively remote sides thereof in the formation of chain-stitches, horizontally disposed and alined rotary shafts carrying said loopers, means for rotating the looper carrying shafts, needle-guards cooperating with the respective needles at the relatively remote sides thereof, and means for moving said needle-guards to and from effective needle-guiding positions.
26. In a hemstitching machine, work-feeding means, a pair of vertically reciprocatory and lat-
- erally vibratory thread-carrying needles arranged abreast with respect to the line of feed, means for relatively vibrating said needles in directions toward and from each other, loop-taking means complementary to said needles in the formation of stitches, a reciprocatory work-penetrating piercer disposed between said needles, a throat-plate provided with adjacent needle-apertures, and a needle-thread-loop guard plate depending from said throat-plate between the paths of reciprocation of the respective needles and having a piercer-slot connecting said needle-apertures, the upper edge of said guard-plate rearwardly of said piercer aperture being depressed below the upper face of said throat-plate to thereby provide clearance for the cross-bars of the hemstitch seam.
27. In a hemstitching machine, work-feeding means, a pair of vertically reciprocatory and laterally vibratory thread-carrying needles arranged abreast with respect to the line of feed, means for relatively vibrating said needles in directions toward and from each other, loop-taking means complementary to said needles in the formation of stitches, a reciprocatory work-penetrating main piercer disposed between said needles, an auxiliary work-penetrating piercer disposed in front of said main piercer in the line of seam formation, and a throat-plate provided with adjacent needle-apertures and with piercer-apertures arranged in the line of feed, the work-supporting face of said throat plate having a work-clearance groove connecting said piercer apertures.
28. A throat-plate for hemstitching machines provided with adjacent needle-apertures and with main- and auxiliary-piercer apertures, said throat-plate having its upper face provided with a work clearance groove connecting said piercer-apertures.
29. A throat-plate for hemstitching machines provided with adjacent needle-apertures and with a piercer-aperture connecting the front ends of said needle-apertures, the upper face of said throat-plate between said needle-apertures being depressed to incline upwardly from said piercer-aperture.
30. A throat-plate provided with adjacent elongated needle-apertures and with a needle-thread-loop guard-plate depending from the under side of said throat-plate, said guard-plate having a needle-aperture separating portion cut away to provide a needle-aperture connecting piercer-slot terminating at its lower end in opposed and downwardly divergent needle-guiding faces.
